UNITED STATES PATENT OFFICE.

FRANK O. HOAGLAND, OF BRIDGEPORT, CONNECTICUT, ASSIGNOR TO UNION METALLIC CARTRIDGE COMPANY, OF BRIDGEPORT, CONNECTICUT, A CORPORATION OF CONNECTICUT.

MUSHROOM-BULLET.

1,114,356.

Specification of Letters Patent. Patented Oct. 20, 1914.

Application filed February 24, 1914. Serial No. 820,622.

To all whom it may concern:

Be it known that I, FRANK O. HOAGLAND, a citizen of the United States, residing at Bridgeport, county of Fairfield, State of Connecticut, have invented an Improvement in Mushroom-Bullets, (Case B,) of which the following is a specification.

This invention relates to full covered or jacketed bullets of the class in which the body cover and the tip cover are made separate, and has for its object to provide a bullet of this type, which, while retaining all the properties of ordinary covered bullets, will mushroom, *i. e.* flatten out, upon impact. This result I accomplish by making cuts entirely through the metal of the tip cover but with the edges closed together which cuts may be made in various different forms, the effect of which is to weaken the cover without removing metal therefrom, leaving the core covered, so that the bullet with the exception of the cuts will have the appearance of an ordinary covered bullet and may be handled like an ordinary full covered bullet, but will, upon impact with an objective, mushroom similarly to an ordinary soft nosed bullet, the tip cover opening out like an umbrella.

In the accompanying drawing forming a part of this specification: Figures 1, 3, 5 and 7, are views showing slightly variant modes in which I have carried the invention into effect; Figs. 2, 4, and 6 are sections on the lines 2—2, 4—4, and 6—6 in Figs. 1, 3, and 5 respectively, looking in the direction of the arrows in each instance; Fig. 8 an end elevation corresponding with Fig. 7; Fig. 9 a sectional view showing a form in which the rear end of the tip cover overlaps the front end of the body cover and also showing independent means for retaining the tip cover in place upon the tapering portion of the bullet; Fig. 10 a sectional view showing a form in which the rear end of the tip cover is closed inward and metal of the core is forced between the contiguous ends of the two covers; Fig. 11 a view partly in elevation and partly in section illustrating the first effect upon the bullet, of impact with an objective, and Fig. 12 is a view showing the bullet completely mushroomed, the tip cover having been opened out over the metal of the forward portion of the core in the manner of an umbrella. The views are all on a greatly enlarged scale.

10 denotes the core of my novel bullet, 11 the body cover and 12 the tip cover.

The gist of the invention lies in weakening the independent tip cover by means of cuts through it in order to cause the tip cover to open out like an umbrella upon impact of the bullet with an objective. In Figs. 1 and 2, I have shown the tip cover as weakened by a plurality of cuts 13 arranged in longitudinal alinement. In Figs. 3 and 4, 65 I have shown the tip cover as weakened by a plurality of circumferential cuts 15 in continuous alinement without breaking joints. In Figs. 5 and 6, I have shown the tip cover as weakened by a greater number of circumferential cuts 16 made shorter and arranged to break joints. In Figs. 7 and 8, I have shown the tip cover as weakened by a plurality of V-shaped cuts 17.

It is wholly immaterial so far as the present invention is concerned whether the rear end of the tip cover overlaps the front end of the body cover, as in Fig. 9, or the rear end of the tip cover is closed inward and core metal forced between the covers, as in 80 Fig. 10.

In the form illustrated in Fig. 9, as a means of insuring the retention of the tip cover upon the tapering portion of the bullet, I preferably strike in holding points 20 85 from the metal of the tip cover and force said points into the core, as clearly shown.

The effect of the weakening of the tip cover by making cuts therein, upon impact of the bullet with an objective is clearly indicated in Figs. 11 and 12. The body portion of the bullet and the body cover will telescope the tapering portion of the bullet, as indicated in Fig. 11, the tip cover being ruptured and opening out like an umbrella. 95 An instant later the entire forward end of the bullet will assume substantially the appearance indicated in Fig. 12.

Having thus described my invention I claim:

1. A bullet comprising a core, a body cover and a separate tip cover, the tip cover being weakened by the formation therein of a plurality of cuts entirely through said cover but with the edges closed together, leaving the core substantially covered, so that upon impact the body portion of the bullet will telescope the forward end thereof and the tip cover will be ruptured and opened out like an umbrella. 105 110

2. A bullet comprising a core, a body cover and a separate tip cover, the tip cover being weakened by the formation therein of a plurality of longitudinal cuts entirely through said cover but with the edges closed together, leaving the core substantially covered, so that upon impact the body portion of the bullet will telescope the forward end

thereof and the tip cover will be ruptured and opened out like an umbrella.

In testimony whereof I affix my signature in presence of two witnesses.

FRANK O. HOAGLAND.

Witnesses:

WILLIAM M. THOMAS,

EDWARD H. ALLEN.
